SPLIT-RING BARREL CLOSURE CONSTRUCTION

Charles T. Draper, Cleveland Heights, and Walter C. Grosser, Cleveland, Ohio, assignors to The Draper Manufacturing Company, Cleveland, Ohio, a corporation of Ohio

Application May 7, 1935, Serial No. 20,198

2 Claims. (Cl. 220—61)

The invention relates to a closure construction for metallic containers, barrels, drums, vessels, packages, pails, kegs, and the like, utilized for shipping, storing and/or dispensing various materials or substances; and relates more particularly to a construction in which a sheet metal cover, closure, head or the like is secured, fastened and sealed onto a metallic container, barrel, drum, vessel, package, pail, keg, and the like, or onto an opening in the head of a metallic container, barrel, drum, vessel, package, pail, keg, and the like.

Numerous constructions have been used for such purposes, but many difficulties have been encountered in the use of the same; either because a special cover closing or fastening machine must be used which must be accurately located with respect to the cover or head in order to secure the same to a container, or because the cover or head, when once secured or fastened in place, is so bent, distorted or damaged upon removal, that it cannot be again used as a satisfactory container cover or head.

The present invention proposes to overcome the difficulties and disadvantages of the prior art in a novel manner and has for an object the provision of a container cover or head, which may be securely clamped, fastened and sealed to a container, or to an opening in the head of a container, without necessarily requiring the use of a special closing and fastening machine.

A further object of the present invention is to provide a container cover or head, which, if a closing and fastening machine is used to clamp, fasten and seal the cover or head to a container, or to an opening in the head of a container, does not require the machine to be specially positioned or located in performing the closing operation.

It is also an object of the present invention to provide a container cover or head closure construction, which construction includes preferably a channel-shaped split-ring, and in which the removal of the split-ring, for taking the cover or head off the container, does not damage the cover or head, but permits the ring and/or cover to be used again and again.

It is likewise an object of the present invention to provide a container cover or head closure construction including a split-ring, in which the cover or head functions satisfactorily and efficiently as such, even though the ring is removed; and in which the cover or head may be provided with a friction fit, if desired, with the container, or with an opening in the head of a container.

Furthermore, it is an object of the present in-

vention to provide a container cover or head closure construction including a preferably channel-shaped split-ring in which the split ring is provided with one or more inwardly extending lugs which may be bent down into a recess in the cover or head to securely hold the split-ring in a position in which it holds the cover or head tightly fastened, clamped and sealed to a container or an opening in the container.

Moreover, it is an object of the present invention to provide a container cover or head closure construction, which, when a clamping, fastening and sealing relation is effected, provides for a continuous and uniform clamping or sealing pressure to be present between the cover or head and the container or the opening in the head of the container, throughout the periphery of the cover or head.

It is also an object of the present invention to provide a container cover or head closure construction in which a gasket is preferably interposed between the cover or head, and the container or the opening in the head of the container, and in which a compressive force is applied to the gasket from both above and below the same throughout its extent.

And finally, it is an object of the present invention to provide an improved container cover or head closure construction which is simple in design, efficient and durable in use, easily assembled or disassembled by the most inexperienced person and low in cost; which also avoids the difficulties and disadvantages of prior art constructions; and which incorporates the aforesaid desiderata.

These and other objects may be obtained by the elements, parts, combinations and constructions constituting the present invention, preferred embodiments of which are shown in the accompanying drawings and are hereinafter described in detail and claimed, and which may be stated in general terms as including, in container cover or head closure construction, a container wall having an outturned annular bead defining an ingress or egress opening for the container, a recessed cover for the container inserted in said opening having a preferably curved peripheral flange, a compressible gasket interposed between said container wall bead and said cover flange, a contractible channel-shaped split-ring embracing said container wall bead and cover flange for compressing the gasket therebetween, said split-ring being provided with one or more inwardly directed lugs bent downwardly into said cover recess for holding the split-ring contracted in cover clamping, fastening and sealing relation,

and said lugs being preferably provided with means for the reception of a tool for bending the same out of recess engagement to permit removal of the split-ring.

5 In the accompanying drawings, in which the present improvements are shown,

Figure 1 is a plan view of a container having a head wall provided with an opening equipped with the improved split-ring closure construction;

10 Fig. 2 is an axial sectional view of a portion of the container shown in Fig. 1, taken on the line 2—2, Fig. 1;

Fig. 3 is a plan view of a contractible channel-shaped split-ring utilized in the improved closure construction shown in Fig. 1;

15 Fig. 4 is a section of the split-ring shown in Fig. 3, taken on the line 4—4, Fig. 3;

Fig. 5 is a sectional view of the cover utilized in

the closure construction shown in Figs. 1 and 2;

20 Fig. 6 is a fragmentary sectional view of the opening in the head wall of the container shown in Figs. 1 and 2;

Fig. 7 is an enlarged sectional view of the closure construction elements shown in Figs. 3, 25 5 and 6, after the same have been initially assembled, and prior to a positioning and locking of the same in cover clamping, fastening and sealing relation;

Fig. 8 is an enlarged sectional view similar to 30 Fig. 7, showing the split-ring after it has been positioned to compress the gasket between the wall bead and cover flange, and diagrammatically showing certain parts of a positioning mechanism;

35 Fig. 9 is an enlarged sectional view similar to Figs. 7 and 8, showing the closure construction elements of Figs. 3, 5 and 6 positioned and locked, in cover clamping, fastening and sealing relation, and diagrammatically showing certain parts of 40 mechanism which may be utilized for effecting the positioning and locking;

Fig. 10 is a plan view, similar to Fig. 1, of a 45 container in which the improved split-ring closure construction is utilized for securing the container head to the container side wall or shell;

Fig. 11 is an axial sectional view, similar to Fig. 2, of a portion of the container shown in Fig. 10, taken on the line 11—11, Fig. 10; and

Fig. 12 is a sectional view, similar to Fig. 9, of 50 certain of the parts shown in Figs. 10 and 11, taken on the line 12—12, Fig. 10.

Similar numerals of reference indicate corresponding parts throughout the various figures of the drawings.

55 Referring to Figs. 1 to 9, inclusive, a sheet metal container, generally indicated at 13, is provided with the improved split-ring closure construction for an opening in the head wall thereof. The container 13 includes a side wall or shell 14, to which a head wall 15 is seamed at 60 16 in the usual manner. The head 15 is preferably provided with a flange 17 in order to offset or recess the head wall 15 from the end of the container.

65 The head wall 15 is provided with a preferably integral tubular neck 18, terminating in an outwardly and downwardly curved peripheral flange 23 (Fig. 5).

The cover flange 22 fits within the tubular neck 18 so that the central wall of the cover 21 is recessed below the outer end of the neck 18, and

5 the fit between the cover flange 22 and the neck 18 may be a friction fit if desired. A preferably compressible tubular annular gasket 24 is interposed between the bead 19 and the curved cover flange 23 for providing a sealed joint or connection between the cover 21 and head wall 15 when the cover is clamped and fastened to the head wall.

A contractible split-ring, generally indicated at 15 25 (Figs. 3 and 4) is utilized in accordance with the present improvements to securely clamp and fasten the cover 21 to the container head wall 15.

The split-ring 25 is channel-shaped in cross section, preferably generally half round and opening radially inward, as best shown at 26 in Figs. 20 4 and 7, and the upper leg 27 of the channel may be preferably slightly flattened at 28. One or more lugs 29 are preferably formed integrally with the ring 25 to extend inwardly (Fig. 3) from the upper flattened channel flange 27—28.

25 A lug 29a, similar to the lugs 29, is preferably provided at each end of the split-ring 25, and the lugs 29 are preferably equally spaced throughout the extent of the split-ring 25 between the lugs 29a. Each lug 29 and 29a is preferably provided 30 with an opening 30 near the inner end thereof for a purpose which will be hereinafter described.

35 The opening 20 in the head wall of a container 13 may be closed with the improved closure construction by proceeding as follows:—

An annular gasket 24 is assembled in the curved flange 23 of the cover 21, as shown in Fig. 5. The cover 21 is then inserted within the neck 18, until the cover assumes a position somewhat as shown in Fig. 7. A split-ring 25 may then be 40 slipped over the curved flange 23 of the cover 21 and the bead 19 of the neck 18 to substantially embrace the container wall bead 19 and cover flange 23 in the position shown in Fig. 7 of the drawings.

45 A closing machine 34 may be applied to the assembled parts, as indicated in Fig. 8 of the drawings, and the jaws 31 thereof provided with extension pads 32 are then operated to press 50 radially at spaced points against the outer periphery of the split-ring 25 to circumferentially contract the split-ring to the position shown in Fig. 8.

The channel 26 of the split-ring 25, in moving from the position shown in Fig. 7 to the position 55 shown in Fig. 8, presses downward from above through its upper leg 27 upon the upper surface of the curved cover flange 23, and presses upward from below through its lower leg 27a upon the underside of the bead 19 whereby a compressive 60 force is applied to the gasket 24 from both above and below the gasket throughout its extent to compress the gasket to the position shown in Fig. 8.

65 The cover is now clamped by the split-ring in a sealing relation with the container wall and a continuous and uniform clamping and sealing pressure is present between the cover 21 and the neck 18 throughout the periphery of the cover 21, because of the application of the clamping and sealing forces to the cover flange 23 and wall bead 19 through the legs of the channel-shaped split-ring 25.

70 A ring or plate 33 of the closing machine 34 may then be operated or moved from the position 75

shown in Fig. 8 to the position shown in Fig. 9, to bend the lugs 29 and 29a downward into the recess in the cover 21, whereby the lugs 29 and 29a constitute discontinuous bendable means 5 which securely fasten the split-ring in cover clamping and sealing relation also shown in Figs. 1, 2 and 9.

Referring to Figs. 10, 11 and 12, inclusive, a sheet metal container generally indicated at 113, 10 is provided with the improved split-ring closure construction for the end opening thereof. The container 113 includes a side wall or shell 114, which terminates in an outturned annular bead or flange 119 to form or define an ingress or egress 15 opening for the container; and the opening is closed by a head 121 having a preferably substantially cylindrical flange 122 at the periphery thereof. The flange 122 terminates in a preferably outwardly and downwardly curved periph- 20 eral flange 123.

The head flange 122 fits within the end of the side wall or shell so that the central wall of the head 121 is recessed below the outer end of the container side wall 114, and the fit between the 25 head 121 and the upper end of the container side wall 114 may be a friction fit if desired. A preferably compressible tubular annular gasket 124 is interposed between the bead 119 and the curved head flange 123 for providing a sealed joint or 30 connection between the head 121 and the container side wall 114 when the head is clamped and fastened to the container.

A contractible split-ring, generally indicated at 125, is utilized in accordance with the present 35 improvements to securely clamp and fasten the head 121 to the container wall 114. The split-ring 125 is channel-shaped in cross section, preferably generally half round, and the upper leg 127 of the channel may be preferably slightly flattened at 128. One or more lugs 129 are preferably formed integrally with the ring 125 to extend inwardly from the upper flattened channel flange 127—128.

A lug 129a, similar to the lugs 129, is provided 40 at each end of the split-ring 125, and the lugs 129 are preferably equally spaced throughout the extent of the split-ring 125 between the lugs 129a. Each lug 129 and 129a is preferably provided with an opening 130 near the inner end thereof for a 45 purpose which will be hereinafter described.

The head 121 may be secured to the container shell 114 in the same manner as has been described in connection with Figs. 1 to 9, inclusive, with the attainment of the same results.

Reference has been made to the use of a closing machine, in describing the assembly of the improved split-ring closure construction. However, the split-ring 25 or 125 may be secured and locked to fasten and seal a cover or head to a container 50 wall without the use of any closing machine, but simply by hammering the lugs 29 and 29a or 129 and 129a from a position such as is shown in Fig. 7, to a position such as shown in either Fig. 9 or Fig. 12.

The split-ring 25 or 125 is contracted and applies compressive forces to the curved cover or head flange and to the wall bead, when the lugs are hammered to bend them downward into the recess of the cover or head.

Moreover, it is unnecessary to specifically position the machine in any particular location with respect to the cover or head or the split-ring, if a closing machine is used for assembling and locking the improved closure construction.

It is only necessary to insert the end of a screw

driver into the lug openings 30 and bend the lugs upward generally to a position such as shown in Fig. 7 of the drawings, at which time the split-ring 25 or 125 may be expanded and removed, whereupon the cover 21 or head 121 may be removed from the container. Such removal of the split-ring and cover or head does not damage the cover or head or ring in any way and each of the same may again be used for providing a clamped, fastened and sealed closure construction. 10

The cover or head may be provided with a friction fit and when inserted in an opening of a container, provides a satisfactory closure for the same as such. Moreover, the improved split-ring closure construction is satisfactory for all sizes 15 and types of metallic containers, either large or small, made of either heavy or light gauge metal and for various sizes of openings for such containers.

Although the thickness of the metal of the split-ring has been shown in the drawings as being substantially the same as that of the container walls and covers or heads therefor, the thickness of the metal from which the split-ring is made may if desired be less than that of the container 25 walls; and likewise the cover or head thickness may be less than the container wall thickness if desired.

The split-ring 25 has been shown as being provided with five lugs and the split ring 125 has 30 been shown as being provided with eleven lugs; but it is to be understood, however, that any desired number of lugs may be provided, and that in the case of small sized openings, it may be necessary to provide only two lugs on the split-ring, one lug at each end of the same.

Moreover, containers equipped with the improved construction may be shipped by a container manufacturer to a user thereof prior to being filled, with the split-ring in the position 40 shown in Fig. 8 of the drawings wherein the same securely holds a cover or head in position during shipment, but wherein the split-ring may be readily removed for removing the cover or head to fill the container with a desired material. 45

Accordingly, the present improvements provide a simple, efficient, durable, easily assembled and low cost closure construction having the desirable characteristics and advantages described, which are not provided by any other known prior art construction. The above description and the drawings referred to therein, are illustrative of structures embodying our invention, and the claims appended hereto are intended to cover 55 such modifications of and slight changes in the structures shown and described, as are apparent to those skilled in the art.

We claim:

1. In closure construction for a metallic container, a wall provided with an outturned flange defining an opening for the container, a recessed cover for the container inserted in said opening having a flange lapping said wall flange, a gasket interposed between said flanges, a replaceable 60 contractible channel-shaped split-ring opening radially inward and embracing said flanges, and said split-ring being provided at intervals with bendable means extending downwardly into said cover recess for contracting and holding the split-ring contracted in cover clamping, fastening and sealing relation.

2. In closure construction for a metallic container, a wall provided with an outturned flange defining an opening for the container, a recessed 75

cover for the container inserted in said opening having a flange lapping said wall flange, a gasket interposed between said flanges, a replaceable contractible channel-shaped split-ring embracing said flanges, and said split-ring being provided with a bendable lug at each end thereof extending

downwardly into said cover recess for contracting and holding the split-ring contracted in cover clamping, fastening and sealing relation.

CHARLES T. DRAPER. 5
WALTER C. GROSSER.
